PROCESSES FOR THE UTILIZATION OF EXHAUSTED LIQUORS

Giacinto Diotti, Milan, Italy, assignor of one-half to **Snia Viscosa, Societa Nazionale Industria Applicazioni Viscosa, Societa per Azioni**, Milan, Italy, an Italian joint-stock company.

Application January 23, 1952, Serial No. 267,739

Claims priority, application Italy January 25, 1951

1 Claim. (Cl. 260—347.9)

A procedure for the utilization of liquors that are discharged after a charge of wood has been digested to obtain cellulose therefrom, and which are termed "exhausted liquors" or in the interest of brevity "liquors," has been specified in applicant's copending patent application, Serial No. 267,740; filed on January 23, 1952.

According to the co-pending application, there can be carried out a process for the production of furfural or other cyclized heterocycles in a thermo-compression evaporator using exhausted liquors having a relatively high pentose content—as for example those which are discharged after a charge of deciduous woods has been digested with bisulphite—the pentoses being converted into furfural thereby heating the liquor up to sufficiently high temperature, the furfural being then removed from liquor in any convenient way, as by the well known distillation systems.

According to the above said copending patent application, the liquor may be submitted to a given concentration, before the pentoses are converted into furfural. The mother liquor, after the furfural has been removed therefrom may be disposed of as a low grade fuel in a known manner, provided it is concentrated up to a sufficient solids content, which may conveniently be about 50%. As is readily appreciated the economy of this process is a function of the ratio of the heat obtained by burning the concentrated liquor, to the heat required to concentrate it. Obviously, the solid matter contents must be selected in such a manner as to have said ratio brought up to highest possible value. Moreover, the manner in which the concentration is effected, particularly with respect to efficiency of concentrators, is also of consequence. Due to economic reasons, same concentrators are practically always of the thermocompression or multi-acting type, for a single stage of thermocompression concentration is to be considered as equivalent to many stages of a conventional concentrator.

This invention relates to an improvement in the procedure in the above referred copending patent application, and is intended to allow a thorough utilization of liquor with the lowest consumption both of reagents and of heat. Such an end can be attained by utilizing the liquor both as a furfural source and as a low grade fuel, and by following a mode of operation such that the heat input will serve at the same time for both of said purposes in conserving the total heat requirement and in returning the fuel to the process as a source of heat. Thus the economy of operational cycle is remarkably improved, and a solution with a relatively high furfural content is obtained from the exhausted liquor wherein the heat requirement is remarkably low.

According to the present invention, the liquor is submitted in a first stage to a concentration amounting only to a part of the final value required for its utilization as a low grade fuel. Then, the pentoses are converted into furfural in the manner disclosed in the application above referred to, whereupon the preliminary concentrated liquor, together with its furfural contents, is brought to a

2

final concentration value, in which the content is obtained of solid matter as required for its utilization as low grade fuel. The furfural formed is removed with the vapors evolved during this final concentration stage, and is collected, under recovery of vaporisation heat, in the form of a condensed liquid, having a relatively high furfural content, and that can be distilled in a very economical manner.

To attain the best operational efficiency, the heating of the liquor, required to cause the conversion of pentoses, can be effected at least partly in counterflow, whereby the liquor coming from preliminary concentration, is heated by the inflowing liquor wherein the furfural has already been formed, and this is cooled before it is brought to its final concentration. The heating can be conveniently effected in two steps—each step under the most suitable pressure. The first step (up to a temperature slightly lower than the maximum value required) is carried out in an heat exchanger, at the expense of the heat given up by the liquor wherein the furfural has already formed; in the second step (term at the over-heating step) the liquor is brought to the maximum temperature by any suitable means. Thus, the costs involved in the heating operations are those springing from heat losses from superheater and heat exchanger, which losses may be minimized by means that are well known. However, the counterflow heating step is not essential, in view of the wide range of thermal and thermodynamic cycles which can be carried out within the limits of the present invention. In the present invention the conversion of pentoses by means of the heating is combined with the concentration of liquor to convert this latter into a low grade fuel, in such a manner that a portion of heat input—which would be at any rate required for such a cycle—is utilized also to separate from liquor a solution showing a relatively high furfural content, which can be then economically submitted to a fractional distillation.

The degree of preliminary concentration of liquor may be varied according to the liquor composition, the concentrator type and also to economical factors. In the usual cases, such a concentration is preferably driven up to attainment of a solids content nearly double that of the original one; however, this is not essential. From an economical viewpoint there is in each case a concentration optimum, and by departing therefrom, the gains that can be drawn from the procedure are reduced, but not nullified—at least up to a certain point. At any rate, it must be remembered that on the one hand it is advantageous that the heating be effected on a highly concentrated liquor, while on the other hand an amount of water sufficient to keep the furfural in solution must be present in the liquor which is delivered for final concentration.

Two embodiment forms of the invention are described—for the purpose of illustration only—in the hereinafter stated examples, taken with the accompanying drawing, in which the Fig. 1 shows diagrammatically the equipment according to Example I, and Fig. 2 shows diagrammatically the equipment according to Example II. It is to be understood that the description is not definitive of the limits of the present invention, for it may be carried into practice by persons skilled in the art in equivalent manners and modifications as are well-known.

Example I

65 The bisulfite liquor in which the digestion of an eucalyptus wood charge has been effected, and that at the end of cooking shows a dry solids content of 160–170 grams per liter—of which 14–16 grams are pentoses—is discharged at a temperature of 100°–110° C. from digester 1 into the tank 2 wherefrom by means of pump 3 it is pumped into the last three elements 4—5—6 of a quadruple effect concentrator, wherein a concentra-

tion is obtained up to a dry solids content of 320-340 grams per liter (of which 32 grams are pentoses) will take place. Then the liquor, as discharged from element 6 of concentrator, is sent by the pump 7, under a pressure of 15-16 kg./sq. cm., to superheater 8, wherein it is heated up to a temperature of 170°-190° C. by means of superheated steam. The capacity of said superheater 8 must be such as to allow the liquor to stay therein for a time of 10-20 minutes. As a consequence of the high temperature attained in the superheater, the pentoses contents of liquor are converted into furfural and therefore the liquor, as discharged from superheater 8, will contain 10-12 grams of furfural per liter. Such a liquor is then sent to first element 9 of quadruple effect concentrator, wherein it is ultimately concentrated until a dry matter contents of 520-560 grams per liter is attained. The whole of liquor furfural contents is removed off together with the vapour evolved from element 9 of quadruple action concentrator, and that is utilized to heat all other elements of same concentrator, whereby a condensed liquid showing a furfural contents of 5-6 percent is discharged from element 6 of concentrator, and then sent to distillation column 10. The concentrated liquor that is discharged from element 9 of quadruple action concentrator, can be directly utilized as a low grade fuel.

Example II

The bisulfite liquor in which the digestion of a charge of common cane (*Arundo donax*) has been effected, and that at the end of cooking shows a dry matter contents of 130-140 grams per liter (whereof 20-25 grams of pentose) is discharged at a temperature of 100°-110° C. from digester 1 into the tank 2, whereupon it is sent by means of pump 3 to thermocompression concentrator 4 in which it is concentrated up to a dry matter contents of 260-280 grams per liter (whereof 40-50 grams are pentoses). The concentrated liquor, discharged from concentrator 4, is sent by the pump 5, under a pressure of 15-16 kg./sq. cm., to heat exchanger 6, where it is brought to a temperature of 150°-160° C. at the expenses of the heat given up by the liquor coming from superheater 7, and that flows in countercurrent through the heat exchanger. Then the liquor is passed from heat exchanger 6 to superheater 7, wherein it is heated from 150°-160° C. up to 170°-190° C. by means of superheated steam. The capacity of said superheater must be such as to allow the liquor to stay therein for a time of 10-20 minutes before it is sent back to heat exchanger 6 where, as aforesaid, it will give up a part of its heat to incoming liquor, being thus cooled from 170°-190° C. down to 120°-130° C. Owing to high temperature attained in the superheater, all pentoses present in the liquor are converted into furfural, whereby same liquor, as discharged from heat exchanger 6, will contain 10-20 grams

of furfural per liter. Such a liquor is then sent to thermocompression concentrator 8, wherein it is concentrated up to a dry matter contents of 520-560 grams per liter. All furfural present in the liquor is passed in the vapours that are evolved during such a concentration, whereby a condensed liquid with a furfural contents of 2-4 percent is obtained. Such a liquid is then sent to distillation column 9, wherein the furfural is distilled off. The concentrated liquor as discharged from concentrator 8, and showing a dry matter contents of 520-560 grams per liter, can be directly utilized as a low grade fuel.

While the invention has been described with some detail, it is to be understood that the description is for the purpose of illustration only and is not definitive of the limits of the inventive idea, as changes may be made therein as fall within the spirit and the scope of the attached claim.

What I claim is:

20 In a process for converting waste bisulfite liquor to furfural and a low grade fuel by evaporation and cyclization in a multiple stage concentrator, that improvement comprising concentrating said liquor to increase its solids content to about twice the solids content of the starting liquor in a first concentration stage at a temperature of 150-160° C. and under superatmospheric pressure, simultaneously cyclizing the pentoses and hexoses in said first stage to form furfural, said furfural evolving as vapor with the water of the liquor, raising the temperature and pressure to about 170 to 190° C. in a second stage of 25 concentration and cyclization, cooling said furfural to about 120-130° C. in a heat exchanger and returning the heat from said heat exchanger to said first stage whereby substantially complete conversion of said pentoses and hexoses into furfural is obtained to provide a concentration of at least 10 to 20 grams per liter and to provide a depleted liquor containing at least 520 grams per liter of solids which is suitable as a low grade fuel, said recovered furfural after condensation being distilled to recover substantially pure furfural.
